H. G. HOUGHTON:
RAILROAD TIE,
APPLICATION FILED JULY 28, 1915.

1,153,387.

Patented Sept. 14, 1915.

HORATIO G. HOUGHTON INVENTOR.

BY *E. J. Bond*

His ATTORNEY.

UNITED STATES PATENT OFFICE.

HORATIO G. HOUGHTON, OF GREEN BAY, WISCONSIN.

RAILROAD-TIE.

1,153,387.

Specification of Letters Patent. Patented Sept. 14, 1915.

Application filed July 28, 1915. Serial No. 42,373.

To all whom it may concern:

Be it known that I, HORATIO G. HOUGHTON, citizen of the United States of America, residing at Green Bay, in the county of Brown and State of Wisconsin, have invented certain new and useful Improvements in Railroad-Ties, of which the following is a specification, reference being had therein to the accompanying drawing.

- 10 The present invention comprises an improvement upon the organization shown in my application No. 40,914 filed July 20th, 1915, which discloses and claims a railroad tie of the general character herein described.
- 15 The claims in the application are limited to such improvement, or detail structure and arrangement, any broader subject matter that may be read upon the railroad tie herein disclosed being claimed, or to be 20 claimed, in said application Serial No. 40,914.

This invention relates to improvements in railroad ties and has for its object the production of a practically indestructible tie 25 provided with shock absorbing end blocks or rail beds.

A further object of my invention is to provide a tie with detachable shock absorbing ends, which ends may be quickly and 30 readily detached and replaced without disturbing the tie proper and without making it necessary to replace the entire tie.

Heretofore in railroad ties of this nature, which have been constructed throughout of 35 concrete, molded in a variety of forms, the rigidity and non-shock absorbing of the material used, causes the tie to crack which entirely destroys the tie, and in several instances caused disastrous results. By the 40 use of my improved tie, danger from this source is entirely eliminated, the end blocks being composed of a fibrous material preferably wood which serves as a bed for the rails and to which they are attached, are 45 joined together by an interposed block of some suitable plastic material preferably concrete or hollow tile. It will be seen that by this arrangement, the wooden bed blocks will efficiently absorb the shocks without 50 danger of cracking the interposed tie.

With these and other objects in view, this invention consists of certain novel combinations, constructions and arrangement of parts as will be hereinafter fully described 55 and claimed.

In the accompanying drawings: Figure 1 is a perspective view of my improved tie, showing the shock absorbing ends secured thereto. Fig. 2 is a perspective view of my improved tie with the shock absorbing ends removed. Fig. 3 is a perspective view of a metal plate used in connection with the tie. Fig. 4 is a perspective view of a shock absorbing end piece or block which is adapted to fit to each end of the tie. Fig. 5 is a longitudinal sectional view in elevation of my complete tie, showing the rails thereon.

Referring to the accompanying drawing, 1 represents the tie proper, which is preferably a rectangular hollow block, having a centrally disposed reinforcing web 2, and is molded preferably of concrete or hollow tile so as to be practically indestructible. At each end of the tie block 1 are transverse V shaped slots or openings 3 adapted to receive a metal lining plate 4.

Rail bed blocks 5 each having a transverse V tongue 6 adapted to fit within the lining plate 4 at each end of the tie block 1 form a bed for the rails. As will be seen by referring to Fig. 5, the metal lining plates 4 lie interposed between the rail bed blocks 5 and the tie 1 so as to form a seat for the tongue 6, also reinforcing the ends of the block 1. These end bed blocks 5 are preferably made of wood which has been previously treated by the creosote process for preserving, the wood being an excellent shock absorber will prevent any excessive shock being transmitted to the tie block 1. 90 Tie bolts 7 screw threaded at each end are adapted to pass longitudinally through the end blocks 5, lining plates 4 and tie 1, the threaded ends of the bolts projecting out past the end face of each of the blocks 5 95 sufficiently to allow nuts 8 to be screwed thereon.

It will be seen that by providing the end blocks 5 with a transverse V tongue 6 adapted to fit the metal lining plates 4, which plates fit into the transverse V slots 3 at each end of the tie block 1, a strong substantial joint is produced when the nuts 8 are screwed home on the bolts 7.

The tie 1 being preferably of hollow construction, will be comparatively light and practically indestructible. The end blocks 5 may be easily renewed without disturbing the tie 1, to do so, the nuts 8 are removed, the blocks 5 may then be slid away from the 110

block 1, new blocks can then be placed there-in and the nuts 8 again screwed home on the bolts 7.

By this arrangement it will be seen that a very simple, cheap and durable shock absorbing tie has been produced, and that the renewing of the end rail bed blocks 5 can be quickly and cheaply accomplished.

Various changes in the form, proportion and the minor details of construction may be resorted to without departing from the principle or sacrificing any of the advantages of the invention as defined in the appended claims.

Having thus described my invention, what I claim is:—

1. A tie comprising an elongated block of plastic material, shock absorbing means adapted to form a bed for the rails secured adjacent each end of said block, reinforcing means disposed intermediate said block and said shock absorbing means, and means for securely joining the said parts together.

2. A tie comprising a rectangular hollow

block composed of plastic material, shock absorbing means composed of fibrous material and adapted to form a bed for the rails secured adjacent the ends of said hollow block, reinforcing plates positioned intermediate said shock absorbing means and said block, and a plurality of tie rods adapted to pass longitudinally through said parts for securely joining the same together.

3. A tie comprising a rectangular hollow block composed of plastic material and having transverse V shaped slots in the opposite ends thereof, reinforcing metal V plates adapted to fit in said V shaped slots, shock absorbing rail bed blocks composed of a fibrous material having V shaped tongues thereon adapted to fit in said reinforcing plates, and a plurality of tie rods or bolts for longitudinally joining the said parts together.

In testimony whereof I hereunto affix my signature.

HORATIO G. HOUGHTON.

Copies of this patent may be obtained for five cents each, by addressing the "Commissioner of Patents, Washington, D. C."
